[57] CLAIM

The ornamental design for a soup bowl, as shown and described.

DESCRIPTION

FIG. 1 is a top perspective view of a soup bowl showing one side of my new design, the opposite side being a mirror image thereof;

FIG. 2 is a top plan view thereof;

FIG. 3 is a front elevational view thereof;

FIG. 4 is a side elevational view thereof;

FIG. 5 is a rear elevational view thereof;
The bottom of the design is substantially flat and unornamented.
